UNITED STATES PATENT OFFICE

WILBUR J. PEETS, OF ELIZABETH, NEW JERSEY, ASSIGNOR TO THE SINGER MANUFACTURING COMPANY, OF ELIZABETH, NEW JERSEY, A CORPORATION OF NEW JERSEY

DESIGN FOR AN ELECTRIC SEWING MACHINE

Application filed October 8, 1932. Serial No. 45,261. Term of patent 14 years.

To all whom it may concern:

Be it known that I, WILBUR J. PEETS, a citizen of the United States, residing at Elizabeth, in the county of Union and State of New Jersey, have invented a new, original, and ornamental Design for an Electric Sewing Machine, of which the following is a specification, reference being had to the accompanying drawings, forming a part hereof.

Figures 1 and 2 are perspective views and Fig. 3 a top plan view of an electric sewing machine, showing my new design; the parts shown in dotted lines being conventional.

I claim:

The ornamental design for an electric sewing machine, as shown and described.

In testimony whereof I have signed my name to this specification.

WILBUR J. PEETS.
